CONVEYOR TOY

Robert D. Pfister, Westport, Conn., assignor to De Luxe Reading Corporation, Elizabeth, N.J., a corporation of New Jersey

Filed Mar. 16, 1965, Ser. No. 84,297

Term of patent 3½ years

(Cl. D34—15)

FIG. 1

The dominant features of my design reside in the portions shown in full lines.

I claim:

The ornamental design for a conveyor toy, substantially as shown and described.
